MUD GUN DEVICE

Tom H. Chrisley, Jr., Bacliff, Tex.

Application January 24, 1952, Serial No. 268,085

4 Claims. (Cl. 299—62)

This invention relates to a mud gun, oscillating device 15 for dispersing a mixture of mud or similar well fluid into a mud mixing pit.

It is an object of this invention to provide a mud gun oscillating device which is moveable arcuately for the dispersion into a pit of mud such as mud used in the 20 drilling of wells, and particularly oil wells.

Another object of this invention is to provide in a mud gun oscillating device an automatically controlled hydraulic cylinder for transmitting its reciprocatory movement through a movement transmitting means to the 25 mud gun for the arcuate transitory movement of the mud gun itself.

Another object of this invention is to provide a mud gun oscillating device in which a mud gun or spray is mounted on a support means with a pivoting or swiveling means associated with the mud gun or spray to enable the gun or spray to move in an arcuate path.

Another object of this invention is to provide in a mud gun oscillating device an automatic control actuating means which includes an hydraulic cylinder with a piston mounted therein for reciprocating movement, the actuating fluid for the piston being supplied through a valve means which enables the actuating fluid to enter at either end of the cylinder alternately, the admission of the actuating fluid being controlled by a valve control means which is pivotally mounted on the cylinder and operatively connected with the valve means and also a frame means associated with the piston so that movement of the piston will be the mechanism for causing the valve control means to operate for reversing the flow of fluid in the valve means to the cylinder.

Another object of this invention is to provide a mud oscillating gun device which is mounted on a support means having associated therewith a swivel mounting means to provide for transitory arcuate movement of the mud gun nozzle, and also having an adjusting means for raising and lowering of the nozzle in a substantially vertical direction to control the point at which the mud being sprayed from the nozzle enters into a mud pit.

Another object of this invention is to provide a device for spraying mud or similar well fluids into a mixing area which includes a spraying nozzle, a support means therefor, a mounting means associated with the support means to provide oscillating movement of the nozzle, a hydraulic cylinder connected with and supported by the support means, which hydraulic cylinder has pistons therein connected with a rod means extending outwardly of the cylinder, a frame means connected to the rod means and including a vertical arm means associated with the swivel mounting means so that movement of the pistons in the cylinder is transmitted through the frame and arm means to the swivel mounting means and thereby moving the mud gun nozzle in accordance with the movement of the pistons in the cylinders.

Other and further objects of this invention will become apparent when the following description is considered in connection with the accompanying drawing where:

2

Fig. 1 is an elevational view of the mud gun device of this invention showing partly in section the hydraulic cylinder device to expose the piston and rod arrangement therefor.

Fig. 2 is a top or plan view taken on line 2—2 of Fig. 1 and illustrates particularly the arcuate path which the mud gun nozzle follows.

Fig. 3 is a detailed sectional view showing the rack and pinion with the attached universal connection of the adjusting means, this view being taken on line 3—3 of Fig. 2.

Fig. 4 is a side elevational view of the mud gun device of the invention illustrating particularly the preferred mode of connecting the hydraulic cylinder and the related structure to the support means or pipe for the mud gun nozzle, this view being taken on line 4—4 of Fig. 1.

The mud gun spray apparatus of this invention includes a spraying nozzle 10 which includes a nozzle tip such as shown at 11 which is threadedly secured by a nut means 12 to an elongate nozzle section 15 which may take various dimensions and shapes as is indicated by a comparison of the lengths shown in Figs. 1 and 4. The particular diameter of the elongate section 15 and the nozzle 10 will depend upon the consistency of the mud or other fluid being handled as well as upon the amount of pressure desired.

The nozzle 10 is supported on a support means 16 which may take the form of a cylindrical pipe 17 as shown in the drawing. This pipe 17 is connected at its lower end with suitable piping leading from a slush or mud pump, not shown.

As part of the support means 16 and immediately above the pipe 17 is located a swivel mounting means 19 which may be a roller or ball bearing mounted pipe section wherein the bearings are located between the flanges 20 and 21. It will be appreciated that bearings are not essential but that flat plates 20 and 21 may be mounted for rotational movement with respect to each other so long as suitable lubrication or non-frictional contact is established. By reason of the swivel mounting means 19 the nozzle 10 can move in an oscillatory or transitory arcuate path which is substantially parallel to ground level. To provide for elevational or vertical adjustment of the nozzle 10 a vertical adjusting means 24 is provided with the swivel mounting means 19. The vertical adjusting means 24 includes a vertical pivot member 25 mounted in fixed relation to the swivel mounting means 19. Mounted on each side of the pivot member 25 are tubes 23. These tubes 23 are received by a nozzle block 22. The ends of each of the tubes 23 are rotatably mounted in the pivot member 25 and the block 22 and suitable sealing means are provided to avoid loss of mud or other fluid passing through the member 25, tubes 23 and block 22.

Connected with the vertical adjusting means 24 is an arm means 26 which includes a vertical upright arm 27 and a connecting link 28. The connecting link 28 is directly connected with the nozzle block 22 at one end thereof and at its opposite end there is located a universal connection 30 which connects with a gear box housing 31. The gear box housing 31 encloses a pinion gear 33 which has a crank shaft 34 connected therewith. At the end of the crank shaft 34 is a handle 35. A rack 36 extends into the gear box housing 31 through openings 37 and 38 therein, the rack 36 forming the upper part of the upright arm 27. Thus, to adjust the nozzle 10 in a substantially vertical direction it is only necessary to grasp the handle 35 and rotate the crank shaft 34 to cause rotation of the pinion 33 for vertical movement of the housing 31 along the rack 36. The vertical movement of the housing 31 is transmitted through the

universal connection 30 and the link 28 to the adjusting means 24 to accomplish the vertical adjustment of the nozzle 10 in either the upward or downward direction to determine the area into which the mud or other fluid is dispersed.

To accomplish the oscillating or arcuate transitory movement of the nozzle 10 an hydraulic cylinder means 40 is provided. This hydraulic means 40 may be suitably mounted on the ground but as best seen in Fig. 4, it is preferably mounted by a horizontal extension 42 connected with the pipe 17, and the valve means 60 is secured to the cylinder means 40 by the support rod 82.

The hydraulic cylinder means includes a fluid cylinder 42 which has therein a piston 43. This piston 43 preferably has a rubber outer coating 44 to provide a satisfactory piston seal and an inner section of metal or other hard material 45 into which fits a rod means 47. The rod means 47 may be composed of two rod sections 48 which are securely attached to the member 45 or in some cases the rod means 47 may be a single rod extending through the piston 43 and having its ends 49 protruding outwardly of the cylinder 42. The ends 49 of the rod means 47 are preferably threaded to receive the nuts 50 which hold the vertical section 52 of the carrier frame 51 in engagement with the rod means 47. The carrier frame 51 also includes a substantially horizontal member 53 which has pivotally connected thereto the upright arm 27. The upright arm 27 is further connected to the horizontal member 54 by braces 56 and 57.

In the movement of the piston 43 back and forth in the cylinder 42, the carrier frame 51 is likewise moved back and forth. This back and forth movement of the carrier frame 51 is transmitted to the arms means 26 which because of the swivel mounting means 19 enables the nozzle 10 to likewise effect a back and forth movement in an arcuate path as illustrated particularly in Fig. 2 wherein the solid line of the nozzle 10 illustrates one position while the dotted line illustrates the extreme other end of the travel of the nozzle 10. Since the support means 16 is fixed it is necessary to provide for a backward displacement of the housing 31 during this arcuate travel of the nozzle 10. This backward travel of the housing 31 is seen in Fig. 4 wherein the solid line indicates the position which the arm 27 would assume at one end of the arcuate travel of the nozzle 10 while the dotted line of the arm 27 and the housing 31 indicates the central point between the extreme position of travel of the nozzle 10. To provide for the backward movement of the arm 27 and the housing 31 the end members 52 are so mounted as to permit a limited rotation about the rod means 47 as can best be seen in Fig. 1.

For regulating the movement of the piston 43 in the cylinder 42 a valve means 60 is provided. This valve means 60 includes a valve cylinder section 61 which has two inlet openings 62 and 63 and two outlet openings 64 and 65 with suitable piping connections therewith. The fluid inlet and piping 62 and 63 have corresponding pipes or tubes 62A and 63A respectively. Likewise the outlet openings or tubes 64 and 65 have corresponding tubes or pipes 64A and 65A respectively. The pipes 62A, 63A, 64A and 65A lead from the upper side of the cylinder 61 to the lower side of the cylinder 42 although it will be appreciated that any suitable positioning of the tube with respect to the two cylinders may be utilized. Within the cylinder 61 are two valve members 67 and 68 which are connected by a hollow tube or sleeve 69. Within the hollow tube or sleeve 69 is a slidable member 71 having a shaft means 72 associated and connected therewith. The outer ends 73 and 74 of the shaft 72 are connected to a bracket 75 which is similar to the carrier frame 51 of the main fluid cylinder 42. Above the bracket 75 is a valve control means 76 which includes a lever 77 pivotally mounted at pivot 78. This pivot 78 is simply a bolt and swivel arrange-

ment on a bracket of U-shape indicated by the numeral 81 in Fig. 4. A clevis or similar bolt arrangement 83 is provided at the end of the lever 77 for connection with the bracket 75. At the upper end of the lever 77 is a counter balancing weight 85 which is mounted with set screws 86 and may be supplemented with movable weights 87 to provide additional counter balance for the valve control means 76.

The operation of the valve control means 76 can best be understood by referring to Fig. 1 and assuming the operation to start from a position with the piston 43 in the left hand side of the cylinder 42 as shown in Fig. 1. When the piston 43 is in the position shown in Fig. 1, the valve members 67 and 68 are closing off the openings of tubes 63 and 64 so that air or other fluid is admitted through the line 62 and thence through the cylinder 61 to the line or tube 62A whereupon the fluid enters the cylinder 42 to cause the piston 43 to move to the right. The valve control means 76 remains in the position shown in Fig. 1 until the left end 90 of the tripping means 89 contacts the lever 77 to move it pivotally about its pivot 78. When the lever 77 reaches a substantially vertical position by reason of the contact with the end 90 of the tripping means 89 the counterbalancing weight 85 causes the lever 77 to move to the extreme right position limited in its movement only by being stopped by the abutment of the bracket 75 with the right end of the valve means 60. This movement of the valve control means 76 causes the bracket 75 to move to the left carrying with it the slidable member 71 which moves through the tube 69 to the left position whereby it contacts and moves the valve member 67 until it contacts the end of the cylinder 61. Since the valve members 67 and 68 are interconnected by the tube 69 both of them are moved upon the movement of one or the other so that when valve member 67 is moved to the extreme left position the valve member 68 likewise moves. This movement of the valve members 67 and 68 cause a closing of the openings of tubes 62 and 65 and an opening of the tubes 63 and 64 whereby fluid is then admitted to the right end of the cylinder 42 through the inlet tubes 63 and 63A. The operation of the valve control device 76 will then function in the opposite manner as the piston 43 moves to the left with air or hydraulic fluid exhausting through tubes 64A and 66. Thus, after limited movement of the piston 43 to the left, the end 91 of the tripping means 89 will cause the lever 77 to move to the left until it reaches a substantially vertical position or just to the left thereof at which point the weights 85 and 87 will cause the lever 77 to move to the left and assume a position as shown in Fig. 1. This leftward movement of the lever 77 is stopped by the abutment of the left portion of the bracket 75 with the valve means 60 or by the contact of the piston 68 with the right end of the cylinder 61 due to its being urged by the slidable member 71. Automatically then the flow of piston fluid to the piston 43 is reversed. Thus, it can be seen that the admission of actuating fluid to the cylinder 42 is controlled so that the actuating fluid is admitted to the opposite ends of the cylinder 42 alternately, which admission is maintained automatically by reason of the valve control means 76 and related structure.

It will be appreciated that the mud or other fluid distributed from the nozzle 10 is fed from a slush or mud pump, not shown, to the lower end of the pipe 17, thence upwardly through the pivot member 25, tubes 23, block 22 and then outwardly through the nozzle 10. This flow of mud will be maintained continuously, if desired, during the oscillation thereof.

It is believed readily apparent from the above description that a mud gun oscillating device has been provided which enables automatic operation of a mud gun in an arcuate path for distributing mud or similar fluid into a mud pit.

Broadly this invention contemplates a mud gun device wherein a nozzle is moved in an oscillatory path by means of an automatically controlled hydraulic cylinder means.

What is claimed is:

1. In a device for spraying well mud in an arcuate path, a spraying nozzle, a support means for said spraying nozzle, a swivel mounting means on said support means operatively connected with said spraying nozzle to provide both for substantially horizontal arcuate movement and independent vertical pivoting movement of said nozzle, an hydraulic actuating cylinder having a piston therein, a piston rod extending from each end of said piston, a carrier frame connected with the end of each said rod exposed outside of said cylinder, said carrier frame having an arm means associated therewith for transmitting movement of said piston to said spraying nozzle, a valve associated with said cylinder for admitting fluid into said cylinder at either end thereof, and a valve control means pivotally mounted on said cylinder and connected with said valve for controlling the operation of said valve so that back and forth movement of said piston in said cylinder is automatically controlled by said valve control means.

2. In a device for spraying well mud in an arcuate path, a spraying nozzle, a support means for said spraying nozzle, a swivel mounting means on said support means operatively connected with said spraying nozzle to provide both for substantially horizontal arcuate movement and independent vertical pivoting movement of said nozzle, an hydraulic actuating cylinder having a piston therein, a piston rod extending from each end of said piston, a carrier frame connected with the end of each said rod exposed outside of said cylinder, said carrier frame having an arm means associated therewith for transmitting movement of said piston to said spraying nozzle, a valve associated with said cylinder for admitting fluid into said cylinder at either end thereof, a valve control means pivotally mounted on said cylinder and connected with said valve for controlling the operation of said valve so that back and forth movement of said piston in said cylinder is automatically controlled by

said valve control means, and a means for adjusting said spraying nozzle in a substantially vertical direction.

3. In a device for spraying well mud in an arcuate path, a spraying nozzle, a support means for said spraying nozzle, a swivel mounting means on said support means operatively connected with said spraying nozzle to provide for substantially horizontal arcuate movement of said nozzle, an hydraulic actuating cylinder having a piston therein, a piston rod extending from each end of said piston, a carrier frame connected with the end of each said rod exposed outside of said cylinder, said carrier frame having an arm means associated therewith for transmitting movement of said piston to said spraying nozzle, a valve associated with said cylinder at either end thereof, a valve control means pivotally mounted on said cylinder and connected with said valve for controlling the operation of said valve so that back and forth movement of said piston in said cylinder is automatically controlled by said valve control means, said arm means having a rack and pinion at its upper end for adjusting said spraying nozzle in a substantially vertical direction.

4. A gun for spraying well muds, comprising, a support member, a spray nozzle, swivel means connecting the nozzle to the support member for both horizontal and vertical swinging movements thereon, fluid pressure actuated reciprocating piston means mounted on the support member, a drive connection between the piston means and the spray nozzle for oscillating the latter in a generally horizontal plane, said drive connection including adjustment means for varying the vertical position of the spray nozzle.
